UNITED STATES PATENT OFFICE

160,983

COMBINATION ERASER AND BRUSH

Edward Wild, West Hartford, Conn., assignor to
The Fuller Brush Company, Hartford, Conn.,
a corporation of Connecticut

Application April 29, 1949, Serial No. 2,348

Term of patent 7 years

(Cl. D74—7)

To all whom it may concern:

Be it known that I, Edward Wild, a citizen of the United States, residing at West Hartford, in the county of Hartford and State of Connecticut, have invented a new, original, and ornamental Design for a Combination Eraser and Brush, of which the following is a specification, reference being had to the accompanying drawing, forming part thereof.

Figure 1 is a plan view of a combination eraser and brush incorporating my new design. Figure 2 is a side view. Figure 3 is a right end view.

I claim:
The ornamental design for a combination eraser and brush, as shown.

EDWARD WILD.
